UNITED STATES PATENT OFFICE

ALBERT BROADMEYER, OF HARRISBURG, PENNSYLVANIA, ASSIGNOR TO THE W. O. HICKOK MANUFACTURING COMPANY, OF HARRISBURG, PENNSYLVANIA, A CORPORATION OF PENNSYLVANIA

EXTENSION-SHEET-DELIVERY MECHANISM

Application filed August 3, 1927. Serial No. 210,376.

The present invention relates to means for receiving sheets that have been operated upon, for example, ruled, and the object is to provide novel mechanism of a simple and effective character, by which a large number of sheets may be received and piled.

The embodiment of the invention herein disclosed is shown in connection with a ruling and interleaving apparatus of the type disclosed in my application, Serial No. 198,548, filed June 13, 1927.

In the accompanying drawings:—

Figure 1 is a plan view of the delivery end of an interleaving machine, showing the receiving mechanism,

Figure 2 is a side elevation of the same,

Figure 3 is a longitudinal sectional view taken on the line 3—3 of Figure 1,

Figure 4 is a detail view in elevation of the operating means for the interleaving feeder and for the receiving mechanism,

Figure 5 is a plan view of the same.

In the embodiment disclosed, a frame 6 is employed, forming the rear end of an apparatus for operating on sheets. This frame includes rearwardly extending side bars 7 arranged in elevated positions and in parallel relation. Journaled in the side bars 7 are cross shafts 8 having sprocket wheels 9. Engaged with these sprocket wheels are hanger sprocket chains 10 that support a sheet-receiving table 11. The shafts carry at their rear ends worm gears 12 that are in mesh with worms 13 carried by a worm shaft 14 journaled on one of the side bars 7. The shaft 14 has a miter gear connection 15 with an operating shaft 16, extending across the frame, and having fixed to its front end a ratchet wheel 17.

Journaled on the front end of the shaft 16 is a swinging pawl carrier 18 having a pawl 19 that operates on the ratchet wheel 17 to intermittently rotate the same. This rotation is in a direction to cause the shafts

8 to turn in a direction to lower the table 11. A hand wheel 20, fixed to a stub shaft 21, is geared as shown at 22 to the shaft 16, so that said shaft can be manually turned in either direction, the pawl 19 of course being disengaged from the ratchet wheel 17 when the

hand wheel is turned in a direction to cause the teeth of said ratchet wheel to turn against the pawl. Journaled on the frame is a drive shaft 23 having a suitable driving pulley 24 that is operated by a belt from any suitable source of power. This drive shaft has an eccentric 25 surrounded by a ring 26 that is carried by an operating link 27. The link has a slotted rear end 28, in the slot of which is engaged a pin 29 carried by the lower end of the pawl carrier 18. It will be understood that the shaft 23 is in constant operation, thereby reciprocating the link 27, and if the pawl carrier 18 is free to move when the link 27 moves rearwardly, the upper end of the pawl carrier swings forwardly, causing the pawl 19 to ride over one or more teeth of the ratchet wheel 17. When the link 27 moves forwardly, the pin 29 is engaged by the end wall of the slot 28, and consequently the pawl 19 is moved rearwardly, turning the ratchet wheel 16. This, through the shaft and worm gearing, rotates the cross shafts 8 and permits the table 11 to move downwardly.

In order to control the downward movement of the table 11, the following mechanism is preferably employed. The pawl carrier 18 has an outstanding stop finger 30, and a latch or detent 31 pivoted at 32 on the frame is adapted to swing to and from a position beneath the stop finger 30. A weighted arm 33 of the latch 31 serves to normally swing said latch out of the path of the stop finger 30. The latch 31 has a link connection 34 with the upper end of a swinging arm 35 pivoted at its lower end as shown at 36 on the frame 6, and fixed to said arm so as to swing therewith is a detector arm 37 having a head 38. This head is adapted to ride along the front side of the pile of sheets 39 that is built upon the table 11, and when the top of the pile falls below the head 38, said head will move over the top margin of the pile, as shown particularly in Figure 4. When so positioned, the arm 35 and link 34 will cause the latch 31 to be moved to a position beneath the stop finger 30, as illustrated in Figure 4.

The arm 35 and detector 37—38 are adapted to be moved by a link 40 having a lost mo-

tion connection 41 in the form of a slot and pin, with the arm 35. The link 40 is pivotally connected to a swinging arm 42 drawn forwardly by a spring 43 against a cam 44 carried by the drive shaft 23. Preferably a 5 roller 45 is journaled in the upper end of the arm 42 and rides the cam 44.

The sheets that have been ruled or otherwise operated upon are delivered to the frame 6 by a conveyor 46 which directs said sheets 10 through a guideway 47 and to a conveyor 48 mounted in the frame 6, said conveyor 48 delivering the sheets onto the table 11. The pile is formed by a rear wall 49 carried by a 15 rod 50 that is adjustably mounted in a hanger 51 supported on a cross bar 52 that is mounted in the rear ends of the frame bars 7. Side jogger walls 53 are suspended from reciprocating rods 54 slidably mounted in the frame bars 7 and operated by eccentrics 55 on a 20 shaft 56.

It will be evident therefore that as the sheets are successively delivered onto the table 11 they will be formed into a pile by the 25 rear wall 49 and between the side jogger walls 53. Whenever the pile of sheets rises to a position above the lower edge of the head 38 of the detector, said detector will be swung forwardly. This causes the arm 35 to move 30 forwardly, releasing the latch 31 so that it will swing forwardly and out of the path of the stop finger 30. When such action occurs, the pawl carrier 18 can swing sufficiently to 35 allow the pawl 19 to ride over the teeth of the ratchet wheel until the link 27 moves forwardly, whereupon the pawl will be engaged with and rotate the ratchet wheel. This will cause a depression of the table 11 until the head 38 rides over the top of the 40 pile. When this occurs, the latch 31 will move to a position beneath the stop finger 30, as shown in Figure 4 and the lowering of the table will cease. On each rotation of the 45 drive shaft 23 the arm 42 will move forwardly, thus moving the link 40 and pulling forwardly the arm 35 and detectors 37 and 38, but the rear movement of said arm 35 and detector 37-38 is each time permitted so that 50 it can move either to a position against the side of the pile of sheets or over the top of the same, depending on the number of sheets that have been added to the pile.

There is shown in connection with the apparatus, an interleaving feeder. This comprises a table 57 suspended by sprocket chains 55 58. The sprocket chains operate over sprocket wheels 59 carried by stub shafts which are also provided with worm gears 60. These worm gears are operated by a cross shaft 61 on which is located a sprocket wheel 62. The 60 sprocket wheel is operated on by a pawl 63 carried by a swinging pawl carrier 64 journaled on the cross shaft 61. The mechanism is substantially that disclosed in the afore- 65 said application, Serial No. 198,548. The

pawl carrier has at its lower end a pin 65 engaged in the slot 66 of a crank arm 67, having an eccentric mounting 68 on the shaft 23. This pawl carrier has a stop finger 69, and a detent latch 70 is adapted to swing into and out of the path of said finger 69. The detent latch has a link connection 71 with a crank arm 72 on a rock shaft 73. The rock shaft is provided with a forwardly extending arm 74 carrying a detector 75 that rests upon the pile of sheets 76 placed on the table 57. A suction feed roller 77 is preferably employed for delivering the sheets from the table 57 and the sheets so delivered are directed between feed rolls 78 and into a guideway 79 that directs said sheets to the conveyor 48.

The table 57 is of course automatically elevated as the sheets are fed therefrom, the elevation depending on the operation of the detector 75. That is to say as the level of the top of the pile decreases, due to the feeding of sheets therefrom, the detector 75 drops, thus carrying the detent latch 70 out of the path of the stop finger 69, allowing the pawl carrier 64 to have a full stroke movement, and thus causing the shaft 61 to operate, rotating the worm gear 60, and sprocket wheels 59 in a direction to cause the ends of the chains fixed to the table 57 to be raised, thus raising the table until the top of the pile elevates the detector 75 and causes the detent latch 70 to reassume its position beneath the stop finger 69.

With this mechanism therefore the sheets are delivered by the conveyor 46 from the table 47 to the table 11 and as the pile on the table 11 grows, said table will be automatically lowered.

From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention.

What I claim, is:

1. In apparatus of the character set forth, 115 the combination with a pile supporting table, of means for delivering sheets thereto to cause them to pile thereon, means for supporting the table, a detector movably mounted below the predetermined top of the pile and having a portion operating against the side of the pile when the top thereof is above the desired level and over the top thereof when said desired level is obtained, and mechanism controlled by the movement allowed the detector 125 for operating the supporting means to lower the table.

2. In apparatus of the character set forth, 130 the combination with a pile supporting table, of means for delivering sheets thereto to cause

- them to pile thereon, means for supporting the table, a pawl and ratchet for operating the supporting means to lower the table, and mechanism for making said pawl and ratchet inactive, comprising a latch and latch operating means including a movable controlling detector that is pivoted below the predetermined level of the pile and having a head that operates against the side and over the top of a pile of sheets formed on the table accordingly as the level of the table top rises above the desired level or falls below said level.
3. In apparatus of the character set forth, the combination with a frame, of intergeared shafts journaled thereon and having sprocket wheels, sprocket chains engaged with the wheels, a pile supporting table suspended from the chains, means for delivering sheets on to the table, a ratchet wheel mounted on one of the shafts, a pawl carrier journaled on said shaft, a pawl on the carrier engaged with the ratchet wheel for rotating it in a direction to lower the table, means having a lost motion connection with the pawl carrier for operating it, a latch for holding the pawl carrier against operative movement, a swinging detector that operates against the side of the pile and over the top of the same and having a connection with the latch to move it, and means for periodically swinging the detector.
4. In apparatus of the character set forth, the combination with a downwardly movable pile support, of mechanism for effecting its downward movement, an upstanding swinging detent for rendering the mechanism inactive, said detent being pivotally mounted at its lower end, a pivotally mounted detector located alongside the pile and having a head that strikes the side of the pile, or moves over the top of the same according to the level of the pile, a link connection between the detent and detector, and means for swinging said detent and detector.
5. In apparatus of the character set forth, the combination with a downwardly movable pile support, of ratchet mechanism for lowering the support, a pivotally mounted detent for rendering the ratchet mechanism ineffective, a pivotally mounted detector having a portion movable against the side of the pile when the top thereof is above a predetermined level and over the top when it is lowered to such level, a swinging arm fixed to the detector and having a link connection with the detent, a link having a lost motion connection with the arm, and means for reciprocating the link.
6. In apparatus of the character set forth, the combination with a vertically movable support for a pile of sheets, of means for varying the height of the pile on the support, and mechanism for automatically moving the support to maintain the top of the pile at substantially a predetermined level, said mechanism including an upstanding automatic feeler movably mounted at a point below the top of the pile and located alongside the upper portion of the pile and having a top portion that abuts against the edges of the sheets or moves over the uppermost when the top of the pile is below the predetermined level.
7. In apparatus of the character set forth, the combination with a vertically movable support for a pile of sheets, of means for varying the height of the pile on the support, and mechanism for automatically moving the support to maintain the top of the pile at substantially a predetermined level, said mechanism including an upstanding automatic feeler pivoted at its lower end and extending upwardly alongside the pile, said feeler having a head on its upper end that abuts the edges of the uppermost sheet when the predetermined level is attained and moves over the top of the pile when the level is lowered below the same.
- In testimony whereof, I affix my signature.
- ALBERT BROADMEYER.
